INDICATOR SWITCH MECHANISM FOR
ELECTRIC RANGES AND THE LIKEKemper M. Hammell, Harrisburg, Pa., assignor to
General Electric Company, a corporation of
New York

Application October 31, 1950, Serial No. 193,258

5 Claims. (Cl. 219—37)

1

This invention relates to electric ranges, and in particular to improved means for closing an electric circuit to a lamp or other signalling device for identification of the switch associated with the surface heating unit on which a cooking utensil has been placed.

In modern electric range design it is the practice to locate the heating unit control switches on an upwardly extending wall or "backsplash" at the rear of the cooking top. This places the switches away from the direct and radiated heat of the surface units, and where the units are grouped at one side of the cooking top affords an opportunity to remove the switches from the cooking zone to avoid concealment of the switches by the cooking vessels or steam emanating therefrom. Although the respective switches are appropriately marked as to the unit which each controls, the separation of the switch from its associated surface unit makes it possible inadvertently to actuate the wrong switch; and it is therefore a principal object of my invention to provide signal circuit means effective whenever a cooking utensil is placed on a surface unit to energize a lamp or other signaling device located at the switch associated with that particular surface unit.

It is another objective of the invention to provide a signal switch organization for the surface units of electric ranges, in which the switch member and its actuator will not interfere with the normal manipulation of the surface unit as it is raised or otherwise handled to permit cleaning or the removal of the reflector pan customarily placed beneath the unit, and are protected against damage during such manipulation.

It is a further objective of the invention to provide a signal circuit switch organization which is of such simple construction that it may be assembled and installed in mass production by unskilled labor but will, nevertheless, be highly reliable in operation over a long service life.

In a presently preferred form of the invention I use a fully enclosed switch—for example, a mercury type switch—pivotally mounted on a bracket directly associated with the mounting of the surface unit in the range. The switch actuator comprises a lever pivotally affixed to the support structure for the heat coil of the unit and extending diametrically of the coil to terminate in operative engagement with the switch mount. A spring biases the lever so as resiliently to maintain the signal circuit switch in open circuit position. A post fixed to the lever and extending upwardly through the heat coil to a position a

2

head portion above the plane of the coil is engaged by the bottom of the cooking utensil and urged downwardly to rotate the lever in switch operating position as the utensil is placed on the heating unit. I prefer to place the actuator post at the center of the heat coil and arrange the lever pivot point so that the mechanical advantage attained thereby insures operation of the switch even when small cooking vessels are used, while permitting enough resistance to operation to avoid switch actuation when an empty vessel of average size is placed on the unit.

Other features and advantages of my invention will be apparent from the following detailed description of a presently preferred embodiment, read in conjunction with the accompanying drawing in which:

Figure 1 is a fragmentary top plan view of an electric range surface unit showing a signal switch and actuator applied thereto; Figure 2 is a vertical elevation of the unit of Figure 1; Figure 3 is an end elevation of the switch element looking in the direction of the arrows 3—3 of Figure 2; and Figure 4 is a vertical section of the switch lever and actuator taken on lines 4—4 of Figure 2.

In Figure 1 a surface heating unit of an electric range comprises a heat coil in which one or more heating elements 2 are arranged spirally to occupy a common plane suitably above and parallel with the cooking top 3 of the range. The heating elements are of the conventional sheathed conductor type and may be arranged in the fashion of the similar elements shown in Sharp Reissue Patent 22,177 of September 8, 1942. The heating elements are maintained in planar relationship by a grid or support having a plurality of rigid arms 4 extending substantially radially from the center of the heating unit.

The arms in turn are supported by a ring 5 which rests on the cooking top 3 about the margin of the opening provided in said top to accommodate the surface heating unit. The respective arms 4 may advantageously be secured relative to ring 5 by tongues 6 projecting through suitable slots in the vertical wall of the ring as clearly appears in Figure 2.

As is well known, the outer sheath of the heating elements 2 is a rigid metal tube, and it is the practice to support the heating unit and its grid and ring assembly for pivotal movement in a vertical plane. Such movement renders the entire unit easily available for cleaning and permits the removal of the conventional reflector pan P (fragmentally shown in Figures 1 and 2)

which customarily occupies the well below the surface heating unit. Accordingly, the rigid end portions 7 of the respective heating elements project through a cutaway portion of the reflector pan, as shown in said Sharp Reissue patent, and through suitable openings in a downwardly extending rigid member 8 comprising a portion of a hinge structure 9 which rotates about a hinge pintle 10 carried by a hinge bracket 11 fixed by conventional means (not shown) to the frame of the range. A leaf spring 12 may be employed to bias the heating unit into its normal position parallel to the range top. The foregoing construction is conventional and forms no part of the present invention.

As the switch element of the signal actuating mechanism comprising my invention, I prefer to use a mercury in glass cartridge 14 of the well known type in which a pair of electrodes are sealed in mutually spaced relationship within the glass envelope and the circuit is completed thereacross by a globule of mercury which travels between open and closed circuit positions as the envelope is tilted about a pivot perpendicular to the path of travel of the mercury. I consider this switch type preferable to conventional mechanically actuated make and break switches for reasons, among others, that the contacts are hermetically sealed and thus completely protected against fouling by grease films which may accumulate over extended periods, the switch is easily removed as a unit for inspection and replacement, and the shock hazard is entirely eliminated. It should be understood, however, that I do not preclude the use of other switch types, although I consider it important that the contacts be completely enclosed. The switch contacts are in a suitable manner connected to the lead 15 which is suitably in a circuit embodying a signal device placed adjacent each control switch for the respective heating units. As previously noted, the control switches are usually mounted on the backsplasher of the range, and it will be understood that the signaling device may comprise an electric lamp associated with a switch such as shown in U. S. Patent No. 2,440,063 granted April 20, 1948, to John L. Andrews.

A switch of the mercury in glass type may be easily mounted for operation as shown in Figures 2 and 3. I utilize a bracket 16 secured to the hinge element 8 and on a rigid wall 17 of said bracket I pivotally affix a cam plate 18. The pivot may advantageously be a rivet 20 or equivalent. The switch envelope and the associated conductor 15 are removably supported in a bracket 21 which may be spot welded to the plate 18. It will be understood that the bracket 21 is of springable metal so that the switch envelope and the lead 15 therefrom may be snapped into place and readily removed. The operation of the switch from open to closed circuit position is accomplished by a lever 22 pivotally attached to a supporting arm 4, as by the ear 22a and rivet 22b. Advantageously, lever 22 is of light sheet metal stock which is formed in inverted U fashion for rigidity. The lever extends diametrically of the heating element and terminates in an offset arm 23 which projects through a guide slot 24 in plate 17 and through a cam slot 25 formed in plate 18 and angularly intersecting the slot 24. A spring 26 fixed to bracket 16 and bearing against the underside of the arm 23 urges the arm upwardly toward the heating element and in such position maintains the switch ele-

ment in the full line Figure 3 position in which the mercury globule is at the end of the glass envelope opposite to the terminals thereof. In other words, spring 26 maintains the switch in open circuit position.

I prefer to affix the lever actuator directly to the lever. An efficient actuator may be in the form of a sheet metal column 28, the bottom portion of which extends beneath lugs 30 stricken outwardly from lever 22 and is welded or otherwise secured to said lugs. The column terminates in a convex cap 31 which normally occupies a plane substantially above that of the heating element as shown in Figure 2. Lateral stability is given to said column by the fingers 32 struck inwardly from opposite sides thereof to lie closely adjacent the sides of the arms 4 as shown in Figure 4. Cap 31 may be secured to column 28 by any suitable means after the heating elements 2 have been placed on the supporting structure.

When a cooking utensil is placed on the surface unit, it will urge the actuator downwardly, thereby rotating the lever 22 counterclockwise of Figure 2. Arm member 23 will drive downwardly along slot 24 and will cam the mounting plate 18 into rotation about the pivot 20. The cartridge 14 will tilt sharply in the direction suggested in dotted lines in Figure 3, and the mercury globule will travel to the opposite end of the cartridge to complete the circuit across the switch terminals. This will serve to complete the circuit to the signal light at the switch (not shown) and designate the backsplasher control switch associated with the particular heating element. I prefer that the lever arrangement be of the second order as illustrated because advantage may be taken of substantially the maximum diameter of the surface unit and mechanical advantages may be established so that although a small cooking utensil placed on the heating unit will have sufficient weight, considering its contents, to actuate the switch, an empty utensil of average size will not be of sufficient weight to move the switch to closed circuit position. It should be understood, of course, that the foregoing comment applies to conventional relatively light weight sauce pans, tea kettles, or the like which frequently are left empty on the cook stove and not to frying pans or heavy cooking pots which ordinarily are stored away.

It will thus be seen that I have provided a simple switch actuating construction which is substantially wholly based upon stamped metal parts capable of assembly in mass production by workmen of ordinary skills. The switch and its actuator are made a part of the surface unit support structure so as not to interfere with the movement of the surface unit about its pivot. The switch cartridge and lead are shielded by the plates 17 and 18 from heat radiated from the surface heating unit, and by their disposition below the cooking top 3, are protected against accidental physical damage.

While there has been described what is at present considered to be the preferred embodiment of the invention, it will be understood that various modifications may be made therein, and it is intended to cover in the appended claim all such modifications as fall within the true spirit and scope of the invention.

What I claim as new and desire to secure by Letters Patent of the United States is:

1. In an electric range having a heat coil supported on a structure including a plurality of radially extending vertically arranged plates, said

structure being carried by a hinge member fixed to the range for pivotal movement of the coil support with respect to said range, an electrical switching system comprising a cam plate pivotally affixed to a wall of said hinge member, a switch unit of the mercury contact type, means for detachably securing said switch unit to said cam plate to be rocked thereby between open and closed circuit positions, a guide slot in said hinge wall member, an elongated cam slot in said cam plate angularly intersecting said guide slot, a lever pivotally carried by said heat coil support near the radially outermost portion thereof and extending diametrically beneath said heat coil, said lever having an arm extending through said guide slot and said cam slot whereby movement of said arm accompanying rotation of said lever will rock said cam plate and the switch unit carried thereby, spring means normally biasing said lever to urge said cam plate into open circuit switch position, and plunger means embracing said lever and projecting upwardly therefrom through the central portion of said heat coil to be engaged and urged downwardly by a cooking utensil placed on said heat coil, to rotate the lever in a direction moving the switch to closed circuit position.

2. Switching means according to claim 1, in which said plunger means straddles said heat coil supporting means and has fingers engageable with side walls of said supporting means for lateral stability of said plunger means.

3. In an electric range having a heat coil supported on a structure carried by a hinge member fixed to the range for pivotal movement of the coil support with respect to said range, an electrical switching system comprising a cam plate pivotally affixed to a wall of said hinge member, a switch unit operable between open and closed circuit positions upon rocking the unit in one or another direction, means for detachably securing said switch unit to said cam plate, whereby the switch unit remains in fixed relation to said heat coil during any pivotal movement of said heat coil support, a guide slot in said hinge wall member, an elongated cam slot in said cam plate angularly intersecting said guide slot, a lever pivotally carried by said heat coil support beneath said coil and having an arm extending through said guide slot and said cam slot whereby movement of said arm accompanying rotation of said lever will rock said cam plate and the switch unit carried thereby, spring means normally biasing said lever to urge said cam plate into open circuit switch position, and plunger means fixed to said lever and projecting upwardly through the central portion of said heat coil to be engaged and urged downwardly by a cooking utensil placed on said heat coil, to rotate the lever in a direction moving the cam plate into closed circuit switch position.

4. In an electric range having a heat coil supported on a structure carried by a hinge structure fixed to the range for pivotal movement into angular relation with said range, a switch of the

mercury in glass type, means for pivotally mounting said switch member on said hinge structure, said switch member being rotatable between open and closed circuit positions, cam means for rotating said switch member, a lever pivotally carried by said heat coil support beneath said heat coil and extending into operative association with said cam means to rotate said switch member upon rotation of said lever, spring means normally biasing said lever to urge said switch member into open circuit position, and plunger means carried by said lever and projecting upwardly through the central portion of said heat coil to terminate in a cap disposed above the upper plane of said heat coil to be engaged and urged downwardly by a cooking utensil placed on said heat coil, thereby to rotate the lever in a direction moving the switch to closed circuit position.

5. In an electric range, a heating unit including a heating element arranged in substantially flat coil form, rigid support means for said element and hinge means having one element secured to said range and a second element secured to said support means whereby said heating unit may be rotated relative to said range; an electric switch, means for mounting said switch on said second hinge element to maintain a fixed position of said switch relative to said heating element at any position of the heating unit relative to said range; means for actuating said switch between open and closed circuit positions; a lever carried by said support means and extending below one of said hinge elements into engagement with said switch actuator for operating said switch to open or closed circuit position according to the direction of rotation of said lever; lever actuating means extending from said lever between convolutions of said heating element to a terminus above the plane of said element, whereby a cooking vessel placed on said heating element will engage said actuating means and by its weight depress said actuating means to rotate said lever in switch circuit closing direction; and spring means engaging said lever to bias the lever into rotation in switch circuit opening direction upon removal of said vessel from said heating element, said last-named direction of rotation restoring the lever actuating means for re-engagement by a cooking vessel, said hinge element interrupting said rotation to establish a fixed relation of said lever actuating means relative to the plane of said heating element.
